ROW CROP HARVESTING ATTACHMENT

David R. Markham, Ottumwa, Iowa, assignor to Deere & Company, Moline, Ill., a corporation of Delaware

Filed Dec. 27, 1966, Ser. No. 5,179

Term of patent 14 years

(Cl. D40—1)

FIG. 1

Des. 209,069

PAGE 2

FIG. 2

FIG. 3

Des. 209,069

PAGE 4

FIG. 4

FIG. 6

FIG. 7

FIG. 1 is a front perspective view of a row crop harvesting attachment embodying my new design;

FIG. 2 is a right front perspective view thereof;

FIG. 3 is a left rear perspective view thereof;

FIG. 4 is a left front perspective view thereof;

FIG. 5 is a front perspective view of a modified embodiment of the row crop harvesting attachment shown in FIG. 1;

FIG. 6 is a right front perspective view thereof; and FIG. 7 is a left rear perspective view thereof.

The broken lines representing the forage harvester are shown for illustrative purposes only.

I claim:

The ornamental design for a row crop harvesting attachment, substantially as shown and described.
